UNITED STATES PATENT OFFICE.

GEORGE RUSSELL, OF MCKEESPORT, PENNSYLVANIA.

DESIGN FOR A COMBINED FIRE-IRON STAND AND COAL-VASE.

SPECIFICATION forming part of Design No. 15,162, dated July 22, 1884.

Application filed April 5, 1884. Term of patent 7 years.

To all whom it may concern:

Be it known that I, GEORGE RUSSELL, of 5
McKeesport, in the county of Allegheny and
State of Pennsylvania, have invented a new
and Ornamental Design for a Combined Fire-
Iron Stand and Coal-Vase; and I do hereby
declare the following to be a full, clear, and
exact description thereof.

My design relates to coal vases or recepta-
cles and fire-iron stands; and it consists in a
coal vase or receptacle and standard for the
fire-irons, having the shape and configuration
shown and described, the same being thus
fully displayed to view in such juxtaposition
as to add greatly to their appearance.

The accompanying drawing is a perspective
view of my design.

The standard *a* of the fire-iron stand *A* has the
bracket *b*, and this standard extends up from

the base *c*. This base has the side extension, 20
d, which corresponds in shape to the coal-vase
E thereon. The base has also the depression
f on its upper surface, and the rim *k* of the
extension *d* of the base forms an ornamental
finish around the base of the coal-vase.

What I claim as my design, and desire to se-
cure by Letters Patent, is—

The design for a combined coal-vase and
fire-iron stand, consisting in a base, a fire-iron
standard, and a coal-vase, of substantially the 30
shape and configuration shown and described.

In testimony whereof I, the said GEORGE
RUSSELL, have hereunto set my hand.

GEORGE RUSSELL.
